UNITED STATES PATENT OFFICE.

GEORGES BARIQUAND, OF PARIS, FRANCE, ASSIGNOR TO S. SMITH AND SONS MOTOR ACCESSORIES LTD., OF LONDON, ENGLAND.

CARBURETOR.

Application filed May 23, 1927, Serial No. 193,655, and in France June 11, 1926.

This invention relates to carburetors for internal-combustion engines of that type comprising an automatic suction-actuated valve sliding vertically within a vertically disposed cylindrical suction-chamber and arranged to cover and uncover successively a plurality of separate straight ducts extending through the cylindrical wall of said chamber, each or each but one of said ducts having a fuel jet delivering into it from a constant-level fuel chamber.

It is the object of the present invention to provide a horizontal carburetor of this type which shall be simple in construction and efficient in operation.

According to the present invention a carburetor of the type described above is provided with a horizontal delivery passage communicating with the suction-chamber through its cylindrical wall and the ducts open into that part of the cylindrical wall of the mixing chamber facing said delivery passage and have their axes parallel to or inclined at a small angle to the axis of the delivery passage, whereby a straight or substantially straight flow of the mixture through the suction chamber is ensured. Preferably the ducts are all situated at the same level and the suction valve is formed with an outlet port constantly registering with the delivery passage, and with a plurality of inlet ports of varying heights, each communicating with the aforesaid port and registering with one of said ducts in such manner that as the valve rises the ducts are uncovered in succession.

Conveniently, the carburetor comprises an annular member which surrounds the suction-chamber constitutes a fuel-supply pipe and supports the fuel jets, and a cap which closes the lower end of the suction chamber and detachably secures said annular member to the suction chamber. The annular member aforesaid may also carry (for example formed integral with it) the constant-level fuel chamber and may also support a fuel jet of a slow-running device, and the suction valve may be retained within the suction chamber by the aforesaid cap; with this construction the removal of the cap allows the annular member with the jets and fuel chamber carried by it and the suction valve, to be removed from the carburetor for cleaning or any other purpose.

An embodiment of the present invention will now be described merely by way of ex-

ample with the aid of the accompanying drawings, in which:

Figure 1 is a vertical section on the line 1—1 of Figure 2 of a carburetor according to the invention.

Figure 2 is a horizontal section on the line 2—2 of Figure 1, and

Figures 3 and 4 show the carburetor in outside elevation and plan respectively.

Like reference numerals indicate like parts in all the figures of the drawings.

The body 1 of the carburetor has a vertically-disposed cylindrical suction-chamber 52 containing the suction-valve 2 which is adapted to slide without rotating. To this end, the suction-valve 2 has a longitudinal groove 3 (see Figure 2) with which engages a key or screw 4 secured to the body 1. The bottom of the suction-chamber 52 is closed by a cap 5 screwed into it, and the top is closed by a screw-cap 51. This cap 51 is provided with a downwardly extending vertical pin 53 and a bored part 54 of the suction-valve 2 is received on it and is guided by it.

The lower cap 5 is provided with an opening into which is screwed a plug 7 provided with a hole. The plug 7 can be changed for one with a larger or a smaller hole for the purpose of regulating at will the depression which is produced in the bottom of the suction-chamber 52 by the movement of the suction-valve 2.

A horizontal delivery-passage 49 opens into the cylindrical wall of the suction-chamber 52 at about the middle of its length. Within the passage 49 there is provided a throttle valve 20 mounted upon a spindle 21 and actuated by a lever 22 in well-known manner. The lever 22 is provided with the usual arm 26 which engages with the usual adjustable abutment 24 to limit the movement of the throttle-valve from its closed to its open position. A flange 19 is provided whereby the carburetor may be bolted on to the engine.

In that part of the cylindrical wall of the suction-chamber opposite to the delivery-passage 49 there are provided three horizontal radiating ducts 8, 9 and 10 arranged in the shape of a fan and having their axes in the same horizontal plane. The axes of these ducts are parallel or inclined at a small angle to the axis of the delivery-passage 49 so that the mixture formed in the ducts will not have to travel round any considerable bends in its

passage through the carburetor. If the mixture has to travel round any considerable bends in the carburetor there is a considerable tendency for the petrol to separate out therefrom with consequential loss of efficiency. It will thus be seen that the absence of any considerable bends in the present construction will be conducive to efficiency.

Surrounding the lower end of the suction-chamber 52, there is an annular member 17 which has formed integral with it the float-chamber 55 and is formed with a fuel conduit 18. Fuel jets 13, 14 and 15 are carried by this annular member and project into the ducts 8, 9 and 10 respectively. The annular member 17 also carries a slow-running jet which feeds the slow-running mixture through passages 35, 38 to a port 37 adjacent to and on the engine side of the throttle valve 20.

The suction-valve 2 is annular in shape and is closed at its bottom so that it will be lifted by the difference in pressure in the suction-chamber above and below its closed bottom. This valve is formed with a port 50 which is always in register with the delivery passage 49 and with three ports 27, 28 and 29 which are adapted to register with the ducts 8, 9 and 10 respectively. The ports 27, 28 and 29 have their lower edges on the level of the upper surface of the bottom of the suction-valve and are of varying length in the direction of the axial length of the suction-valve. The port 27 is of such length that when the suction-valve is at the bottom of the suction-chamber, as shown in Figure 1, the port partly registers with the duct 8 and places it in communication with the suction chamber. The port 28 is of such length that when the valve is at the bottom of the suction-chamber, it will just not register with the duct 9 which does not, therefore, communicate with the suction-chamber. The port 29 is of less length than the port 28.

As the throttle valve 20 is opened, a strong suction is produced in the suction-chamber 52 and the suction-valve 2 will be elevated by the air-pressure under it due to the leakage from the hole in the plug 7. As the valve lifts, it will first fully uncover the duct 8, then uncover the duct 9 owing to the port 28 registering with the latter and will finally uncover the duct 10 owing to the port 29 registering with the duct. The amount of lift of the valve will be dependent upon the amount of opening of the throttle as is well known in this type of carburetor.

Extra air passages 42 are provided one communicating with each of the ducts 8, 9 and 10, and opening into a flat vertical face of the carburetor. A flat rotary valve 39 is secured by means of a stud 40 on to this flat face and is formed with ports 41 adapted to

register with the extra air passages 42. This valve may be operated in any desired manner, such as by a rod secured at 43 to it, and serves to allow extra air to pass through the passages 42 and ducts into the suction-chamber when so desired.

It will be noted that the carburetor is simple to construct and that the removal of the cap 5 allows the carburetor to be completely dismantled since both the suction-valve 2 and the annular member 17 with the parts secured to the latter are retained in the carburetor by the cap 5 only.

This invention is not limited to the precise constructional detail described above and is capable of many modifications.

What I claim:

1. A carburetor comprising a vertically disposed cylindrical suction chamber, a horizontal delivery passage communicating with the suction chamber through its cylindrical wall, a plurality of separate straight ducts opening into that part of the cylindrical wall of the suction chamber facing said delivery passage and being substantially aligned with the delivery passage, an automatic suction-actuated valve slidable in said suction-chamber and arranged to cover and uncover the ducts successively, an annular member constituting a fuel supply pipe and surrounding said suction chamber, a plurality of fuel jets carried by said annular member and extending into said ducts and a cap which closes the lower end of the suction chamber and detachably secures said annular member to the suction chamber.

2. A carburetor comprising a vertically disposed cylindrical suction chamber closed at its upper end, a horizontal delivery passage communicating with the suction chamber through its cylindrical wall, a plurality of separate straight ducts situated at the same level and opening into that part of the cylindrical wall of the suction chamber facing said delivery passage and being substantially aligned with the delivery passage, an annular member surrounding said suction-chamber, a fuel supply passage in said annular member, a plurality of jets carried by said annular member, an automatic suction actuated valve slidable in said suction-chamber and formed with an outlet port constantly registering with said delivery passage and a plurality of inlet ports of various heights, each adapted to register with one of said ducts, and a cap formed with a vent hole, closing the lower end of said suction-chamber and detachably securing said annular member to the suction chamber.

In witness whereof I affix my signature.

GEORGES BARIQUAND.
